UNITED STATES PATENT OFFICE.

JOHN J. HEEDY, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A DRINKING VESSEL OR SIMILAR ARTICLE.

42,850.

Specification for Design.

Patented Aug. 6, 1912.

Application filed May 8, 1912. Serial No. 696,001. Term of patent 14 years.

To all whom it may concern:

Be it known that I, JOHN J. HEEDY, a citizen of the United States, and residing at Moundsville, in the county of Marshall and State of West Virginia, have invented a certain new, original, and ornamental Design for a Drinking Vessel or Similar Article, shown in the accompanying drawing, which is a view in perspective of the same.

I claim:

The ornamental design for a drinking vessel or similar article, as shown.

JOHN J. HEEDY.

Witnesses:

A. J. MONTGOMERY,
C. E. WOOD.
